US00D919101S

(12) **United States Design Patent** (10) Patent No.: **US D919,101 S**
(45) Date of Patent: **** May 11, 2021**

(54) **PORTABLE BLOOD GLUCOSE METER**

(71) Applicant: **LG Electronics Inc.**, Seoul (KR)

(72) Inventors: **Dana Jung**, Seoul (KR); **Yihyun Moon**, Seoul (KR); **Byungsoo Kim**, Seoul (KR)

(73) Assignee: **LG Electronics Inc.**, Seoul (KR)

(**) Term: **15 Years**

(21) Appl. No.: **35/508,635**

(22) Filed: **Jul. 12, 2019**

(80) **Hague Agreement Data**

Int. Filing Date: **Jul. 12, 2019**

Int. Reg. No.: **DM/205929**

Int. Reg. Date: **Jul. 12, 2019**

Int. Reg. Pub. Date: **Feb. 14, 2020**

(57) **CLAIM**

The ornamental design for portable blood glucose meter, as shown and described.

DESCRIPTION

1. Portable blood glucose meter

1.1 : Perspective

1.2 : Front

1.3 : Back

1.4 : Left

1.5 : Top

1.6 : Bottom

1.7 : Reference view

1.8 : Reference view 2

1.9 : Reference view 3

The broken lines depict portions of portable blood glucose meter that form no part of the claimed design; reproduction 1.7 is a reference view showing the state in which the claimed design is opened like forceps; reproduction 1.8 is a reference view showing the state in which the claimed design is combined with a band; reproduction 1.9 is a reference view showing the state in which the claimed design is combined with a band and the display part is operated; this is a design for a portable blood glucose meter; as shown in reproduction.
